INVENTOR.

UNITED STATES PATENT OFFICE.

HENRY ZAHN, OF NEW YORK, N. Y.

IMPROVEMENT IN FURNACES AND PROCESSES FOR MANUFACTURING COKE AND GAS.

Specification forming part of Letters Patent No. 150,808, dated May 12, 1874; application filed September 27, 1873.

To all whom it may concern:

Be it known that I, HENRY ZAHN, of the city, county, and State of New York, have invented certain Improvements in Furnaces, of which the following is a specification:

By means of these improvements certain calorific powers of coal and other fuels, which are now wasted, are utilized. By these improvements, also, both the smoke and the combustible gases are consumed and a superior article of coke produced.

Thus are accomplished the following three-fold objects: first, an abatement of dirt; second, an increase of heat; and third, a decrease in the consumption of fuel.

This new invention unites in one furnace a fire-chamber with a coke-oven. This coke-oven is entirely distinct from what other applicants for patents have called "coking-chambers." These so-called coking-chambers can never make coke, for the reason that they are more or less open, and are only partially separated from the fire-chamber. My coke-oven is capable of being entirely closed, and is absolutely separated from the fire-chamber. Another of the distinguishing excellencies of my coke-oven is the arched roof or dome. By means of this dome the orifice of escape for the smoke, the sublimates, the gases, and the heat is contracted. This contraction of the orifice both retards the escape of the heat and diminishes its waste. This retardation of heat tends to the greater purity, solidity, uniformity of texture, and general heat-producing powers of the coke. This perfecting effect of time on coke is accounted for on the well-known principles of crystallization. This dome-shaped roof also, on the equally-familiar principles of radiation, concentrates a greater intensity of heat on the coke below, and thus still further adds to its power and perfections as a fuel. The smoke, sublimates, and gases which are freed by the fires of the coke-oven are, by the other appliances which I have incorporated in this furnace, conveyed to, under, and through the grate-bars of the fire-chambers. On these grate-bars of the fire-chamber is the coke-fuel, which was made in the coke-oven, and for the reasons that the fuel produced in that oven is the most perfect. For these same reasons the

waste products which are freed by the first fire are more thoroughly consumed by the second.

When the furnace is applied to smelting processes another much-desired and long-sought-for object is attained by this invention and the production of a purer and stronger metal. By the old furnaces, some of the freed products of combustion enter into and deprave its qualities. This source of weakness is especially deplored in the manufacture of iron and steel. The second furnace consumes these elements, and so, of course, saves metals from being debased by them.

All the main features of this invention will now be described in connection with the accompanying drawings, in which—

Figure 1 is a vertical cross-section through the coke-oven and the fire-chamber combined. Fig. 2 is a diagram of the same above the grate-bars.

At A is shown the coke-oven. They are generally lined with fire-bricks or other blocks molded expressly for such purposes. The shape may be square at the bottom externally and circular inside, as indicated in the section at A in Fig. 2. When carried up to the necessary height, (according to the purpose for which it is intended,) it is covered with an arched dome of the same fire-clay material. In the center of this dome, as at B, is an opening for the admission of raw coal to be coked. This coke-oven is entirely inclosed, as at C, by an outer wall or walls of metal or other suitable material. In or between these walls are constructed flues or chambers through which to conduct the waste products of the process of coking; also to convey the air-blast to the fires. These exterior walls serve also as supports to the coke-oven itself, as is shown in Fig. 1. These walls serve the further purpose of supporting the working-chamber and fire-grate, as at D, in Fig. 1. This purpose, however, is not essential. The coke-oven and the fire-chamber may be arranged on separate frames. All that is necessary is that the coke-oven and the fire-chamber be in such proximity that the coke and the waste products from the coke-oven may be readily transferred to the grate-bars of the fire-chamber (either by a drop-bottom, an inclined plane, or otherwise) by

the force of its own gravity. The bottom of the coke-oven A is placed, as shown in Fig. 1, on an incline, and is pivoted either at the side or to a shaft in the center, so as to be readily tilted to the position indicated by the dotted lines at E. By means of this incline or drop bottom the coke may readily be dropped upon the chute or apron F into an intermediate distributing-chamber, which last improvement is not indicated in the drawings. In some uses of this furnace this intermediate or coke-distributing chamber will be necessary. In other applications it will not. In some instances it will be desirable to introduce into this intermediate chamber a cylindrical or other appliance, by which to discharge into the fire-chamber a smaller or larger quantity, nicely graduated to the requirements of the occasion. Here, as in many other features of the furnace, each and every application will require a specially modified adaptation. The coke-oven, when full, contains several times more coke than, for some purposes, is required to charge the fire-chamber at any one time. This makes the distributing-chamber in such cases a necessity, even as to quantity. But different applications of the furnace require not only different quantities of coke, but different grades as well. The demands of some purposes are met by a thirty-six hour coke, while other purposes vary between this grade all the way up to ninety-six hour coke. This distributing-chamber enables us to nicely adapt both quality and quantity to the various requirements of the fire-chamber, and to the different uses to which the furnace, as a whole, is applied. From this distributing-chamber the coke is conveyed, as I have said, into the fire-chamber, and in varying quantities, according to the different uses to which the furnace is applied. The aforesaid chute F is pivoted at its lower edge, and is operated by a rack and pinion, as at G. The pinion-shaft is worked by a crank on the outside of the frame, but a toggle-joint, or other appliance which would be equally convenient, may be adapted to it. Underneath the coke-oven there is placed, as at H, an air-chamber, into which air may be forced by a fan or its equivalent, and at any desired pressure. By means of this fan appliance air may be supplied to the coke-oven through suitable perforations, substantially as represented by the arrows a a, and in greater or less quantities, as may be required in the process of coking. The products of combustion, which escape through the opening B in the top of the coke-oven, will be carried over into the outer chamber L to a flue at M. Here it is caused to combine with a current from the fan, and which current carries the smoke, sublimates, and gases, through a conduit, as at N, to and underneath the grate-bars of the fire-chamber, as at D. In the fire on and over the grate-bars, at D in the fire-chamber, these waste products of the first combustion are completely utilized, in passing through the incandescent fire of the second

combustion. The fan may be placed at O, or it may be made to connect at some point with the flue N. The hot-air blast may be controlled by a valve, as at P. This valve is a portion of the partition. It is pivoted in such manner that it may be placed either against one side or other of the flue, or at intermediate points between both sides. By means of these various devices the valve may either throw part of the blast into M and N, or nearly all of it into N, and only enough into M to sustain the necessary supply of air in the coke-oven. At R is shown a door or opening in the side of the coke-oven A, which may be used for cleaning it, and also, when necessary, for repairs. At S, at the top of the chamber L on the outer wall C, is an opening through which to supply the coke-oven with coal. The coal is guided down to the opening B by the hopper or funnel at S. This opening at the top is provided with a cover. Doors may be provided in the air-chamber H below the coke-oven for closing it; also for repairs. A damper is shown at T in the ash-pit, under the grate-bars of the fire-chamber. This may be used, when it is desirable, to admit air without the blast from the fan. Between the fire-chamber and the coke-oven a hollow wall of fire-brick is provided. This serves to protect the outer wall of the coke-oven; also to heat the cold air for the hot-blast by the fan. The openings in this wall are connected with a flue which leads to the fan or flue M and N at O. The flues M and N may be provided with a pipe, as at V, communicating with a steam-generator or boiler, so that a small quantity of moisture may be made to commingle with the gases from the coke-oven.

In some applications of this invention the whole furnace will be supplied with a system of water-jackets, and which are not indicated in the drawings herewith presented. These water-jackets will serve to absorb still more of the heat which would otherwise escape by radiation. They will provide a supply of hot water for steam-boilers instead of cold, and they will thus contribute to save the furnace itself from the self-destroying effects of its own fires.

Having explained the uses and workings of the general devices which make up the coal-saving furnace by reference to the drawings, I will now proceed to narrate the various processes and operations in the order of time, beginning with the first act and proceeding in order through the successive steps and stages, down to the last.

The first thing to be done is to kindle a fire in the coke-oven, then charge the oven with coal through the funnel at S. In this condition the smoke, the sublimates, and gases are confined within the coke-oven, and they might be kept there until combustion would cease in the coke-oven for want of air. To prevent this extinction of the fire a small supply of air is furnished through the small apertures at a, by means of a fan or other draft. This will

establish a current of air by which to carry off the unconsumed carbon into the flue N, and thence onward to and underneath the grate-bars at D. Here these waste products will be consumed, as we shall see, in the incandescent fire, which will presently be deposited on these grate-bars. When the coal in the coke-oven is sufficiently coked the side of the fire-chamber (or intermediate distributing-chamber, as the case may be) is lowered by means of a crank, and made to form a chute, as at S. The bottom of the coke-oven, also by means of a crank, drops down, and the charge of coke, by the force of its own weight, is in a moment transferred from the coke-oven into the intermediate or distributing chamber at D. A duplication of the same appliances, and a repetition of the same means, which transferred the coke from the coke-oven to the intermediate or distributing chamber, will now (with the addition of a revolving-cylinder or other convenient appliance) deliver the coke in quantities to suit from the distributing to the fire chamber. A second charge of coal is now lowered into the coke-oven, while the oven itself is yet glowing hot, and the oven at once proceeds, without any reheating, as in the first instance, to manufacture a second supply of coke.

Having thus fully described my invention, what I claim as new, and desire to secure by Letters Patent, is—

1. The combination of a coke-oven, in which the waste products of combustion are partially or wholly confined, with a working chamber or heating-grate, by means of a flue or flues, which serve to conduct and control the current of these products into the fire of said chamber or grate, and whereby said waste products of the first combustion are utilized.

2. In combination with a coke-oven, with devices for confining the gases and admitting air in regulated quantities, the perforations in the walls of the coke-oven, by which air is heated with which to supply a hot-air blast,

and by which also the outer walls of the coke-oven are preserved from destruction by its own fires.

3. In combination with a coke-oven, with devices for confining the gases and admitting air in regulated quantities, the system of mechanical contrivances, whereby the coke can readily be transferred from the chamber of production to the chamber of consumption, by the force of its own gravity, by this means avoiding the necessity of moving and lifting the coke by hand-power into position on the grate-bars of the fire-chamber.

4. In combination with a coke-oven, with devices for confining the gases and admitting air in regulated quantities, an intermediate or distributing chamber, from which coke can be conveyed in varying and graduated quantities according to the will and wishes of the operator, and according to the requirements of the different uses to which the furnace is applied.

5. In combination with a coke-oven, with devices for confining the gases and admitting air in regulated quantities, a fan, by which air may be supplied in any desired quantity, to both the coke-oven and the fire-chamber, and which serves also to establish a current with which to carry off the unconsumed carbon into the flues.

6. In combination with a coke-oven, with devices for confining the gases and admitting air in regulated quantities, a system of water-jackets, by which heat is saved and used for heating feed-water for steam-boilers and other purposes.

7. The method herein described for producing hard and compact coke, consisting in confining the gases more or less as described, and regulating the admission of air so as to prolong the operation of coking, as set forth.
